dustries, Inc., Chicago, Ill., a corporation of
Delaware

Application October 22, 1947, Serial No. 781,377

15 Claims. (Cl. 84—1.19)

1

The present invention relates to electrical musical instruments, and, more particularly, to an electronic organ of novel and improved character.

In my U. S. Patent No. 2,486,039 dated October 10, 1949, I have disclosed an electrical musical instrument which essentially comprises at least one series of cascaded aperiodic frequency-halving trigger circuit stages and a master pulse generator supplying pulses of audio-frequency to one of said stages whereby output pulses of octavely related frequencies may be derived from the remaining stages. In general, trigger circuits of the Eccles-Jordan type were found to be the most satisfactory for instruments of the described character due to their simplicity of structure and their great reliability in operation. As is well known, in the Eccles-Jordan circuit a pair of space discharge tubes are connected with a network of capacitors and resistors and a source of direct current potential in such a manner that the circuit has two stable states of equilibrium in which the two tubes are alternately conducting. When a train of negative pulses is applied to the control grids of the two tubes, the conducting state is shifted from one tube to the other for each successive pulse. Pulses of one-half of the frequency of the original input pulses may be derived from one of the tubes of the first stage and may be applied to the grids of the tubes of the next stage, and so forth. Thus, from a series of cascaded Eccles-Jordan stages it is possible to derive octavely related output pulses having frequencies of $f/2$, $f/4$, $f/8$, $f/16$, etc., when the frequency of the pulses applied to the first stage is f . Although the practical advantages of a generating system of the described character are numerous and are fully set forth in my aforesaid co-pending application, perhaps the most important single advantage is that in the resistor-capacitor networks associated with each stage the corresponding resistances and capacitors are of equal values. This greatly increases the simplicity of assembly in contrast to the present cascaded oscillator stages almost exclusively employed in conventional electrical musical instruments where each stage has to be individually tuned to its desired operating frequency by proper selection of the circuit components.

The signals of octavely related frequencies obtained from cascaded Eccles-Jordan circuits are generally characterized by a waveform of square shape. As is known to those skilled in the art, the harmonic composition of a square wave may be represented by the following formula:

$$y = \frac{4}{\pi} E \left(\cos x - \frac{1}{3} \cos 3x + \frac{1}{5} \cos 5x - \frac{1}{7} \cos 7x \dots \right)$$

2

It appears that the output signal comprises only the odd harmonics of the fundamental frequency and that the even harmonics are absent. Since the simplest and most convenient way of obtaining various musically valuable tone colors from a complex wave is predicated upon filtering out the undesired harmonics from the said wave, this circumstance greatly reduced the number of distinct tone colors obtainable in an electronic organ employing Eccles-Jordan frequency dividing circuits.

I have now discovered that this disadvantage may be fully eliminated and the outstanding problem may be solved in a remarkably simple manner.

It is an object of the present invention to provide an electrical musical instrument having a system of generators originally producing square waves or other similar waves comprising a generally incomplete series of harmonics which are converted into waves characterized by a substantially unbroken series of harmonics.

It is another object of the present invention to provide an electronic organ comprising audio-frequency signal generators characterized by a square wave output which is converted into a saw-tooth wave output suitable for conversion into musically valuable tone colors of great variety.

The invention also contemplates an electronic organ of novel and improved character capable of producing audio-frequency signals of both square and sawtooth wave form which may be individually treated by suitable filters for the production of a practically unlimited range of tone colors simulating most of the conventional orchestral instruments.

Other and further objects and advantages of the present invention will become apparent from the following description, taken in conjunction with the accompanying drawings, in which

Figures 1 and 2 collectively constitute the circuit diagram of an electronic organ, embodying the principles of the present invention.

Broadly stated, according to the principles of the present invention, signals of square waveform are converted into sawtooth waves by combining several square waves having octavely related frequencies and predetermined relative amplitudes with respect to each other.

The frequency relationship of the harmonics of a square wave follow like the odd numbers of the series of integers:

1, 3, 5, 7, 9, 11, 13, 15, 17, 19, 21, 23, 25 . . .

55 A square wave signal of twice the frequency will have harmonics the frequencies of which will relate to the fundamental frequency of the first series, as follows:

2, 6, 10, 14, 18, 22, 26, 30, 34, 38, 42, 46, 50 . . .

A square wave signal of four times the frequency will have harmonics the frequencies of which will relate to the fundamental frequency of the first series, as follows:

4, 12, 20, 28, 36, 44, 52, 60, 68, 76, 84, 92, 100 . . .

Combining the foregoing three series, the following composite series will be obtained, omitting the harmonics above 23:

1, 2, 3, 4, 5, 6, 7, 9, 10, 11, 12, 13, 14, 15, 17, 18, 19, 20, 21, 22, 23 . . .

It will be noted that the series of harmonics is completely unbroken up to the eighth harmonic. Also, up to the twenty-fourth harmonic, the only harmonics absent are the eighth and the sixteenth. It can be readily shown both mathematically and experimentally that a series of the described character provides a sawtooth wave with excellent approximation which is fully satisfactory for all practical purposes. Of course, the closeness of approximation may be further increased by adding further square waves of higher octavely related fundamental frequencies although this would be hardly necessary or desirable in a practical and commercial electronic organ. Provided that the amplitude relation of the combined square wave signals of octavely related fundamental frequencies is properly selected, the result will be with very close approximation a sawtooth wave of the following harmonic composition:

$$y = \frac{2E}{\pi} \left(\sin x - \frac{1}{2} \sin 2x + \frac{1}{3} \sin 3x - \frac{1}{4} \sin 4x \dots \right)$$

I have discovered that the foregoing principle of producing complex waves containing a substantially unbroken series of harmonics by combining octavely related less complex waves containing only the odd harmonics of their respective fundamentals is admirably suited for further improving the performance of electronic organs employing aperiodic frequency dividing trigger circuits of the general type disclosed in my aforesaid co-pending application.

Referring now more particularly to Figs. 1 and 2 of the drawing, the electrical musical instrument diagrammatically illustrated therein comprises a master oscillator M, a pulse sharpener circuit P, five cascaded frequency-halving stages of the Eccles-Jordan type F-1 to F-5, and an output circuit.

Master oscillator

The master oscillator M is a generator of audio-frequency oscillations of a generally sinusoidal character and having a notably constant frequency. It comprises a pentode tube T-0 having a plate 10, a suppressor grid 11, a screen grid 12, a control grid 13 and a cathode 14. Plate 10 is connected to B plus lead 15 through a resistance R-1. The audio-frequency oscillations are produced in a tuned tank circuit composed of capacitor C-1 and inductance L-1, one terminal of which is connected to control grid 13 through a grid condenser C-2 and the other is connected to ground lead 16. R-2 is a grid resistor connected between the control grid and ground in the conventional manner. Tank inductance L-1 is coupled to another smaller inductance L-2 connected between cathode 14 and ground and providing feedback between the grid and cathode circuits. The tank circuit may be tuned by means of a powdered iron core 17 which is axially displaceable in inductance L-1. A relatively large capacitor C-3 is connected between the "hot" terminal of the tank circuit and plate

10. Screen grid 12 is connected to the midpoint of two resistors R-3 and R-4 arranged between B plus lead 15 and ground lead 16 and is effectively grounded for audio frequencies through a bypass capacitor C-4.

As is more fully disclosed in Patent No. 2,489,497 to James A. Oswald, a circuit of the described character will produce electrical oscillations of a sinusoidal frequency determined by the circuit constants, particularly those of the tank circuit, the said frequency being conveniently adjustable by means of movable iron core 17. These oscillations may be frequency-modulated by applying an audio-frequency oscillation of a frequency of about 6 to 8 cycles per second to suppressor grid 11, to obtain a vibrato effect.

Pulse sharpener circuit

The function of the pulse sharpener circuit P is to convert the sinusoidal output signal of the master oscillator into a series of sharp pulses, suitable for triggering the following cascaded frequency-divider stages F-1 to F-5.

While a great variety of different pulse sharpening circuits may be used for the purposes of the invention, in its illustrated form the pulse sharpener or pulse peaker circuit comprises a pair of triodes T-1 and T-2, which are preferably combined in a single envelope constituting a twin triode.

Triode T-1 comprises a plate 20, a control grid 21 and a cathode 22, while triode T-2 comprises a plate 23, a control grid 24 and a cathode 25. Plates 20 and 23 are connected to B plus lead 15 through plate resistors R-11 and R-12, respectively, and cathodes 22 and 25 are connected to ground through cathode resistors R-13 and R-14, respectively.

Output signal from the master oscillator is applied to triode T-1 through a network comprising a capacitor C-5 and resistor R-15 serially connected between plate 10 of tube T-0 and ground, their midpoint being connected to control grid 21 of tube T-1 through a high resistance R-16, acting as a grid limiter. Plate 20 of tube T-1 is connected to ground through a differentiating network comprising a capacitor C-11 and a resistor R-17, the midpoint of the said capacitor and resistor combination being directly connected to grid 24 of triode T-2. By suitable selection of the circuit constants more fully disclosed in the table forming part of the present description, it may be readily obtained that the sinusoidal oscillations derived from master oscillator M will appear in the form of sharp, well-defined negative pulses at the plate 23 of triode T-2. In view of the fact that pulse sharpening circuits of the described character are well known to those skilled in the art and do not form part of the present invention, it will not be necessary to give a detailed description of their operation.

Frequency divider stages

The frequency divider circuits, of which five, F-1 to F-5, are provided in cascaded arrangement, have the function of dividing the input pulse frequency by the factor of 2 per stage.

Referring more particularly to frequency divider stage F-1, it comprises a twin triode T-3, T-4. Triode T-3 has a plate 30, a control grid 31 and a cathode 32, triode T-4 has a plate 33, a control grid 34 and a cathode 35. Plates 30 and 33 of the said twin triode are connected to B plus lead 15 through plate resistors R-21 and R-22, respectively, cathode 32 is connected to

ground 18 through cathode resistor R-23; while cathode 35 is directly grounded.

Plate 30 of triode T-3 is connected to input point 36 of the frequency divider circuit through serially connected resistors R-25 and R-26. Likewise, plate 33 of triode T-4 is connected to the same input point 36 through serially connected resistors R-27 and R-28. Input point 36 is connected to a source of negative C bias voltage (lead 37) through a resistor R-29.

Grid 31 of triode T-3 is connected to the common point of resistors R-27 and R-28 and grid 34 of triode T-4 is connected to the common point of resistors R-25 and R-26. Small capacitors C-21 and C-22 are connected across resistors R-25 and R-27, respectively, for reasons which will appear presently.

Frequency divider circuits F-2 to F-5 respectively include twin triodes, T-5, T-6; T-7, T-8; T-9, T-10; and T-11, T-12. The tube elements and the circuit elements of these circuits and their connections are identical with those of circuit F-1 and the reference numerals applied thereto have been derived from the numerals of the respective elements in circuit F-1 by adding 10, 20, 30 and 40 thereto. In view of the identical arrangement of the several frequency divider circuits, it will be sufficient to describe the operation of the first one, F-1.

Referring now to frequency divider circuit F-1 in Fig. 1, this is a modification of the well-known Eccles-Jordan trigger circuit in which resistive networks are associated with the elements of two triodes in such a manner that at any time only one of the two triodes can be conducting. Thus, assuming that triode T-3 is initially conducting, the respective values of resistors R-21, R-25, R-26 and R-29 are so determined with respect to the B and C voltages and to the tube characteristics that a negative bias beyond cutoff will be applied to grid 34 of triode T-4, maintaining the same in the non-conducting state. Likewise, should T-4 be initially conducting, T-3 will be maintained in the non-conducting state as a result of the symmetrical arrangement of the two resistive networks. Either one of these states will persist indefinitely in the absence of an external signal.

Again assuming that triode T-3 is conducting and that a strong negative pulse is applied to input point 36, this pulse will have no appreciable effect upon grid 34 of triode T-4 which is already biased negatively beyond cutoff. However, the same negative pulse simultaneously applied to grid 31 of triode T-3 will momentarily render it sufficiently negative to cut off the plate current of the said tube. As soon as the plate current stops to flow and the voltage drop across resistor R-21 is greatly reduced, grid 34 of tube T-4 will be rendered positive, sufficiently so as to render tube T-4 conducting. This in turn will apply a negative bias beyond cutoff to grid 31 of tube T-3, maintaining it in the non-conducting state initiated by the negative pulse. In other words, a single negative pulse applied to the input point 36 has the effect of transferring the conducting state from one triode to the other, in the instant case from T-3 to T-4. Another negative pulse will again transfer the conducting state from T-4 back to T-3. It will be readily understood that a train of negative pulses applied to point 36 will cause the conducting state to alternate between tubes T-3 and T-4 at half the rate of the applied pulses so that pulses at half of the input frequency may be withdrawn from either one of

the two triodes. Thus, it will be seen that the circuit will function as a frequency divider, dividing any input frequency by the factor of 2.

Condensers C-21 and C-22, respectively connected across resistances R-25 and R-27 are effective in improving the triggering effect in that they permit transmittal of the reversing pulses to the corresponding grids practically instantaneously, without the delaying effect of the resistors through which the pulses had to travel in the absence of the said capacitors.

While the foregoing explanation of the operation of the Eccles-Jordan trigger circuit merely approximates the actually much more complex dynamic conditions existing in circuits of the described character, it is considered to be sufficient for the purposes of the present description, particularly as those skilled in the art are familiar with the principles underlying to the operation of circuits of this type.

The negative triggering pulses of a frequency f are applied to the first frequency divider stage F-1 by means of a coupling capacitor C-20 connected between plate 23 of pulse sharpening tube T-2 and input point 36 of triodes T-3 and T-4. Pulses of a frequency $f/2$ are applied to frequency divider stage F-2 by means of a similar coupling capacitor C-30 connected to grid 34 of triode T-4 and through lead 19 to input point 46 of triodes T-5 and T-6. Pulses of a frequency $f/4$ are applied to frequency divider stage F-3 by means of capacitor C-40 connected between grid 44 of triode T-6 and input point 56 of triodes T-7, T-8. Pulses of a frequency $f/8$ and $f/16$ are applied to frequency divider stages F-4 and F-5, respectively, by capacitors C-50 and C-60 connected between grids 54 and 64 of triodes T-8 and T-10, respectively, and input points 66 and 76 of triodes T-9, T-10 and T-11, T-12, respectively.

It has been noted in the foregoing that all of the frequency divider circuits F-1 to F-5 are identical in character and in their circuit arrangement and that the reference numerals of the various circuit components and tube elements have been obtained from those of divider circuit F-1 by adding 10 for each of the circuits. All of the corresponding capacitors and resistors are of equal value in all divider circuits. Although in the drawing only five frequency divider stages have been shown, any suitable number may be employed and the principle of frequency division may be extended indefinitely. Thus, pulses of a frequency $f/32$ may be passed on to an additional stage (not shown) through lead 76 connected to grid 74 of tube T-12, etc. For example, in an electronic organ covering the musical range of 7 octaves, it will be generally necessary to provide 7 frequency divider stages.

Output circuit

Output signal of octavely related frequencies may be drawn from any portion of each frequency divider stage. In the illustrated form of the invention, the output signal is obtained across cathode resistors R-23, R-33, R-43, R-53 and R-63. These resistors are of relatively low value to avoid unbalancing the otherwise fully symmetrical arrangement of the Eccles-Jordan circuit although, if desired, a similar cathode resistor may be introduced into both branches of each stage. Signal may be drawn from either or even both branches of each stage and in this connection it is to be considered that the signals drawn from the two cathodes of each stage are 180 degrees

out-of-phase. In general, it is preferred, however, to draw the output signal from the cathode of the triode which does not supply triggering pulse to the next stage as this results in greater stability of the system.

The instrument of the invention permits producing both square wave signals and sawtooth wave signals which may be selectively utilized in order to obtain a greater variety of musically useful tone qualities.

The square wave output system comprises leads 80, 81, 82, 83, 84 and 85 connecting cathodes 22, 32, 42, 52, 62 and 72 of tubes T-1, T-3, T-5, T-7, T-9 and T-11, respectively, to keying switches K-1, K-2, K-3, K-4, K-5 and K-6, respectively, through decoupling resistances R-80, R-81, R-82, R-83, R-84 and R-85, respectively. The working contacts of all of these switches are connected to square wave output bus bar O-1. In this connection, it may be observed that the signal flowing through lead 80 is drawn from the pulse sharpener stage P and is not a true square wave but a clipped sine wave. However, for all practical purposes the difference between the clipped sine wave and the square wave is not significant for musical purposes and the described procedure of obtaining output signal also from the pulse sharpener stage makes it possible to save one frequency divider stage in the instrument. The sawtooth wave output system comprises output terminals 90, 91, 92, 93, 94 and 95. Of these:

Terminal 90 is connected to cathode 25 of tube T-2 through decoupling resistor R-90.

Terminal 91 is connected to output lead 81 through decoupling resistor R-91 and to cathode 25 of tube T-2 through decoupling resistor R-92 and lead 96.

Terminal 92 is connected to output lead 82 through decoupling resistor R-93, to output lead 81 through resistor R-94 and lead 97 and to cathode 25 of tube T-2 through resistor R-95 and lead 97.

Terminal 93 is connected to output lead 83 through resistor R-96, to output lead 82 through resistor R-97 and lead 98, and to output lead 81 through resistor R-98 and lead 98.

Terminal 94 is connected to output lead 84 through resistor R-99, to output lead 83 through resistor R-100 and lead 99, and to output lead 82 through resistor R-101 and lead 99.

Terminal 95 is connected to output lead 85 through resistor R-102, to output lead 84 through resistor R-103 and lead 100, and to output lead 83 through resistor R-104 and lead 100.

Of course, the system can be extended to further lower frequency stages, if such are provided, decoupling resistors R-105 and R-106 and lead 101 being illustrated for this purpose, connecting to an additional output terminal (not shown).

It will be readily observed that, in general, each output terminal is connected to three square wave output leads of adjoining octavely related frequencies through decoupling resistors of suitably selected values so that an approximately sawtooth wave-shaped signal will appear at such terminals. While terminal 90 is connected to only one output lead, the clipped, differentiated sine wave signal drawn will to some extent approximate a sawtooth wave shape. Also, terminal 91 is connected to only two output leads. However, the resulting absence of certain of the higher even harmonics will be hardly noticeable to the musical ear since many of the said harmonics are be-

yond the audible frequency range. The decoupling resistors associated with the same output terminal are of progressively decreasing values in order to approximate the relative amplitudes of the corresponding higher harmonics to the respective amplitudes of such harmonics present in a sawtooth wave. Thus, R-102, R-103 and R-104, connected to terminal 95 may have values of 50,000, 100,000 and 200,000 ohms, respectively, and terminals 94, 93, 92, etc. may have decoupling resistors of similar values associated therewith.

A normally open switch K-7, K-8, K-9, K-10, K-11 and K-12 is connected between sawtooth wave output bus bar O-2 and output terminals 90, 91, 92, 93, 94 and 95, respectively.

Square wave output bus bar O-1 is connected through a normally closed switch K-13 to three quality control or stop switches K-14, K-15 and K-16. The working contacts of the said three switches are connected to a main output bus bar O through quality filters Q-1, Q-2, Q-3 and decoupling resistors R-110, R-111, R-112, respectively.

Sawtooth wave output bus bar O-2 is connected through a normally closed switch K-17 to three quality control or stop switches K-18, K-19 and K-20. The working contacts of the said three switches are connected to main output bus bar O through quality filters Q-4, Q-5, Q-6, and decoupling resistors R-113, R-114, R-115, respectively.

Main output bus bar O is connected to an amplifier A and the amplified audio-frequency oscillations are converted into musical sounds by a loudspeaker S.

Operation

From the foregoing description, the operation of the electrical musical instrument embodying the invention will be readily understood by those skilled in the art. The circuit constants of master oscillator M are so adjusted that it produces sinusoidal oscillations of a frequency f which equals the frequency of one of the notes (for example C) of the highest octave of the instrument. These sinusoidal oscillations are converted into sharp negative pulses of the same frequency by pulse sharpener circuit P. These pulses are introduced into the series of aperiodic, cascaded frequency divider circuits F-1 to F-5 so that pulses of frequencies $f/2$, $f/4$, $f/8$, $f/16$ and $f/32$ will appear in the respective cathode circuits. The result will be square wave-shaped signals of such respective frequencies at switches K-1 to K-6, and sawtooth wave shaped signals of equal respective fundamental frequencies at switches K-7 to K-12.

Preferably, pairs of the said switches (K-1 and K-7; K-2 and K-8; K-3 and K-9; K-4 and K-10; K-5 and K-11; K-6 and K-12) are operable by the same key (B-1, B-2, B-3, B-4, B-5 and B-6, respectively) of a playing manual, such mechanical connection being indicated in the drawing by dotted lines connecting the respective coordinated switches. Upon depression of any key, both square wave and sawtooth waves of the same fundamental frequency are introduced into output bus bars O-1 and O-2, respectively. The harmonic composition of the oscillations present is modified by the filters Q-1 to Q-3 and Q-4 to Q-6, respectively, according to the open or closed condition of stop switches K-14 to K-16 and K-18 to K-20. Thus, as illustrated in Fig. 2, filter Q-2 is effective as to the square wave output bus bar O-1

Inductances

L-1 4500 turns of No. 33 wire.
 L-2 1300 turns of No. 33 wire.

and filter Q-4 is effective on to the sawtooth wave output bus bar O-2. Of course, stop switches K-14 to K-16 and K-18 to K-20 may be actuated in any desired combination in accordance with the requirements of a musical composition.

Switches K-13 and K-17 are normally closed and, when opened, are instrumental in completely disabling the square wave and sawtooth wave output of the instrument, respectively, regardless of the setting of stop switches K-14 to K-16 or K-18 to K-20.

The oscillations of modified harmonic compositions are introduced into the main output bus bar O and after amplification are rendered audible by speaker S.

The quality filters Q-1 to Q-6 may be of any suitable type capable of changing the relative amplitudes of the harmonics of a complex wave. Quality filters suitable for the purposes of the invention are disclosed, for example, in my U. S. Patent No. 2,403,664 or in the Larsen Patent No. 2,403,090. I have found that square wave signals, upon appropriate filtering, are particularly suitable for producing the flute and diapason type tone qualities, whereas sawtooth wave signals, upon appropriate filtering are particularly suitable for producing the tone qualities of string and reed instruments in an electronic organ.

It will be noted that in a complete electronic organ 12 systems of the type illustrated in Figs. 1 and 2 are provided, corresponding to the 12 steps of the equally tempered scale. In view of the fact that all of the said 12 systems are identical as to their circuit and operation and merely differ in the frequency of the master oscillators, it will not be necessary to illustrate and to describe the same. For details of such organs reference may be had to my aforesaid Patent No. 2,486,039. Of course, the output bus bars O-1, O-2 and O and the associated filters, stop switches, amplifier and speaker may be the same for all 12 note systems in a practical electronic organ.

The electrical values of the elements as numbered and lettered on the drawings and several circuits and networks and preferred types of vacuum tubes employed are approximately, as follows:

Resistances

1, 11, 12, 25, 27, 29, 35, 37, 39, 45, 47, 49, 55, 57, 59, 65, 67, 69, 80—85, 92, 94, 97, 100, 103, 106; 100,000 ohms.

2, 15, 17, 470,000 ohms.

3, 4, 26, 28, 36, 38, 46, 48, 56, 58, 66, 68; 56,000 ohms.

13; 5,000 ohms.

14; 4,000 ohms.

16; 1,000,000 ohms.

21, 22, 31, 32, 41, 42, 51, 52, 61, 62; 43,000 ohms.

23, 33, 43, 53, 63; 2700 ohms.

90, 91, 93, 96, 99, 102; 50,000 ohms.

95, 98, 101, 104, 105; 200,000 ohms.

Condensers

1; 0.03 microfarads.

2; 0.002 microfarads.

3; 0.02 microfarads.

4; 0.05 microfarads.

11; 0.0003 microfarads.

20; 0.00005 microfarads.

21, 22, 30, 31, 32, 40, 41, 42, 50, 51, 52, 60, 61, 62; 0.0003 microfarads.

Tubes

T-0; 6SK7.

T-1, T-2; T-3, T-4; T-5, T-6; T-7, T-8; T-9, T-10, T-11, T-12; 7F7.

The preferred value of the B plus voltage is about 115 volts above ground potential and that of the C minus voltage is about 150 volts below ground potential.

Although the present invention has been disclosed in connection with a preferred embodiment thereof, variations and modifications may be resorted to by those skilled in the art without departing from the principles of the present invention. I consider all of these variations and modifications to be within the true spirit and scope of the present invention, as disclosed in the foregoing description and defined by the appended claims.

What is claimed is:

- 25 1. In an electrical musical instrument, the combination which comprises a master oscillator adapted to produce sinusoidal audio-frequency oscillations of constant frequency, a pulse sharpener circuit to convert said oscillations into a train of pulses, a series of cascaded aperiodic frequency-halving trigger circuit stages responsive to said pulses by the generation of octavely related pulses of complex wave form characterized by a harmonic composition from which certain of the harmonics are absent, a plurality of output terminals and coupling elements for supplying signals from selected respective groups of octavely adjoining stages to each of said terminals resulting in composite signals of complex wave form at said terminals characterized by a practically unbroken series of harmonics.
- 30 2. In an electrical musical instrument, the combination which comprises a master oscillator adapted to produce substantially sinusoidal audio-frequency oscillations of constant frequency, a pulse peaker circuit to convert said oscillations into a train of sharp pulses, a series of cascaded aperiodic frequency-halving trigger circuit stages of the type responsive to said train of sharp pulses by the generation of a set of pulses of complex wave form characterized by octavely related fundamentals and by a harmonic composition in which only the odd harmonics are present, a plurality of output terminals, and conductive paths supplying signal from selected groups of octavely adjoining trigger circuit stages to each of said terminals and making available at such terminals modified signals having a complex wave form and including a practically unbroken series of harmonics.
- 35 3. In an electrical musical instrument, the combination which comprises a master oscillator producing sinusoidal constant audio-frequency oscillations, a pulse peaker circuit converting said oscillations into a train of sharp pulses, a series of cascaded aperiodic frequency-halving trigger circuit stages of the Eccles-Jordan type responsive to said train of sharp pulses by the generation of a set of octavely related square wave pulses, a plurality of output terminals, and conductive paths of generally different impedance supplying signals at predetermined relative amplitudes from selected groups of trigger circuit stages to each of said terminals and making sawtooth wave signals of octavely related funda-

- 40 ments.
- 45 4. In an electrical musical instrument, the combination which comprises a master oscillator producing sinusoidal constant audio-frequency oscillations, a pulse peaker circuit converting said oscillations into a train of sharp pulses, a series of cascaded aperiodic frequency-halving trigger circuit stages of the Eccles-Jordan type responsive to said train of sharp pulses by the generation of a set of octavely related square wave pulses, a plurality of output terminals, and conductive paths of generally different impedance supplying signals at predetermined relative amplitudes from selected groups of trigger circuit stages to each of said terminals and making sawtooth wave signals of octavely related funda-
- 50 ments.
- 55 5. In an electrical musical instrument, the combination which comprises a master oscillator producing sinusoidal constant audio-frequency oscillations, a pulse peaker circuit converting said oscillations into a train of sharp pulses, a series of cascaded aperiodic frequency-halving trigger circuit stages of the Eccles-Jordan type responsive to said train of sharp pulses by the generation of a set of octavely related square wave pulses, a plurality of output terminals, and conductive paths of generally different impedance supplying signals at predetermined relative amplitudes from selected groups of trigger circuit stages to each of said terminals and making sawtooth wave signals of octavely related funda-
- 60 ments.
- 65 6. In an electrical musical instrument, the combination which comprises a master oscillator producing sinusoidal constant audio-frequency oscillations, a pulse peaker circuit converting said oscillations into a train of sharp pulses, a series of cascaded aperiodic frequency-halving trigger circuit stages of the Eccles-Jordan type responsive to said train of sharp pulses by the generation of a set of octavely related square wave pulses, a plurality of output terminals, and conductive paths of generally different impedance supplying signals at predetermined relative amplitudes from selected groups of trigger circuit stages to each of said terminals and making sawtooth wave signals of octavely related funda-
- 70 ments.
- 75 7. In an electrical musical instrument, the combination which comprises a master oscillator producing sinusoidal constant audio-frequency oscillations, a pulse peaker circuit converting said oscillations into a train of sharp pulses, a series of cascaded aperiodic frequency-halving trigger circuit stages of the Eccles-Jordan type responsive to said train of sharp pulses by the generation of a set of octavely related square wave pulses, a plurality of output terminals, and conductive paths of generally different impedance supplying signals at predetermined relative amplitudes from selected groups of trigger circuit stages to each of said terminals and making sawtooth wave signals of octavely related funda-

mental frequencies available at such terminals.

4. In an electrical musical instrument, the combination which comprises a plurality of generators producing octavely related audio-frequency oscillations of complex waveform characterized by identical but octavely transposed harmonic composition from which certain of the harmonics are absent, a plurality of output terminals, and a plurality of coupling elements for each of said terminals respectively connected between the terminal and an output point of a corresponding generator sequentially selected from a group of octavely adjoining generators of increasing frequency, the first one of said elements supplying from the lowest frequency generator to the terminal signal of complex waveform from which certain of the harmonics are absent, and the others of said elements additively supplying from the higher frequency generators to said terminal signals of complex waveform including substantially all of said absent harmonics whereby the resultant composite signals of complex waveform at each of said terminals will be characterized by a practically unbroken series of harmonics.

5. In an electrical musical instrument, the combination which comprises a plurality of sources of octavely related audio-frequency oscillations of complex waveform characterized by the presence of the odd harmonics and by the absence of the even harmonics, a plurality of output terminals, and a plurality of conductive paths for each of said terminals respectively connected between the terminal and an output point of a corresponding source sequentially selected from a group of octavely adjoining sources, the first one of said paths supplying from the lowest frequency source to the terminal signal of complex waveform from which the even harmonics are absent, and the others of said paths additively supplying from the higher frequency sources to said terminal signals of similar but octavely transposed complex waveform including substantially all of said even harmonics thereby providing at said terminals octavely related signals of complex waveform including a substantially unbroken series of harmonics.

6. In an electrical musical instrument, the combination which comprises a plurality of sources of octavely related audio-frequency oscillations having a substantially square wave output, a plurality of output terminals, and a plurality of conductive paths for each of said terminals connected between the terminal and a group of octavely adjoining sources, the first one of said paths having such impedance as to supply square wave signal of predetermined amplitude from the lowest frequency source to the terminal, and the others of said paths having such impedances as to supply square wave signals of progressively decreasing amplitude from the higher frequency sources to said terminal, the relative impedances of said paths being so adjusted as to additively combine the octavely related square wave signals into a wave form practically approximating a saw tooth wave at said terminal.

7. In an electrical musical instrument, the combination which comprises a plurality of sources of complex audio-frequency oscillations the fundamentals of which decrease as the successive powers of 2 and the harmonic composition of which is substantially restricted to odd harmonics, an output terminal for each of said sources, and a plurality of resistive paths for each of said terminals respectively connected between the terminal and an output point of a corresponding

source sequentially selected from a group of octavely adjoining sources, the first one of said paths supplying from the lowest frequency source to the terminal signal of complex waveform from which the even harmonics are absent, and the others of said paths additively supplying from the higher frequency sources to said terminal signals of similar but octavely transposed complex waveform including substantially all of said even harmonics thereby to produce at the terminals output signals characterized by a series of harmonics which is unbroken up to a certain limit harmonic, said limit harmonic being determined by the number of sources to which each terminal is connected by said plurality of resistive paths.

8. In an electrical musical instrument, the combination which comprises a series of sources of complex audio-frequency oscillations the fundamentals of which decrease octavely and the harmonic composition of which is substantially restricted to odd harmonics, a series of output terminals, and a set of three resistive paths for each of said terminals respectively connecting the corresponding terminal to the output points of three of said sources adjoining to each other in the series thereby to produce output signals of complex waveforms at such terminals, the fundamental of each of said signals equaling the fundamental of the source of the lowest frequency to which the corresponding terminal is connected and the harmonic composition of said signals being characterized by an unbroken series of harmonics at least up to and including the seventh harmonic.

9. In an electrical musical instrument, the combination which comprises a plurality of sources of octavely related audio-frequency oscillations of complex waveform characterized by the substantial absence of the even harmonics, a plurality of output terminals, a plurality of conductive paths for each of said terminals respectively connected between the terminal and an output point of a corresponding source sequentially selected from a group of octavely adjoining sources, the first one of said paths supplying from the lowest frequency source to the terminal signal of complex waveform from which the even harmonics are absent, and the others of said paths additively supplying from the higher frequency sources to said terminal signals of similar but octavely transposed complex waveform including substantially all of said even harmonics thereby providing at said terminal a modified signal of complex waveform including a practically unbroken series of harmonics up to a desired harmonic, an output circuit, and switches interposed between said terminals and said output circuit to render said modified signals selectively effective in said output circuit.

10. In an electrical musical instrument, the combination which comprises a series of sources of octavely related square wave oscillations of audio frequency, a plurality of output terminals, resistive paths supplying square wave signals at predetermined relative amplitudes from selected groups of octavely adjoining sources to each of said terminals and combining such signals into octavely related sawtooth wave signals at the several terminals, an output circuit, a key-controlled switch interposed between each of said terminals and said output circuit adapted when actuated to render said sawtooth wave signals selectively effective in said circuit, a sound producing means, and a filter network connected between said output circuit and said sound pro-

ducing means to change the harmonic composition of the signals applied to the sound producing means.

11. In an electrical musical instrument, the combination which comprises a series of sources of octavely related square wave oscillations of audio frequency, a plurality of first output terminals, a conductive path connected between each first terminal and a corresponding source supplying square wave signal of predetermined frequency to said first terminal, a plurality of second output terminals, a set of conductive paths for and connected between each second terminal and a corresponding group of octavely adjoining sources and having such relative impedances as to additively combine the square wave signals drawn from said group of sources into a saw tooth wave at the said second terminal, an output circuit, and a key-controlled switch interposed between each first and second terminal and said output circuit adapted when actuated to render signals of different wave form and of different frequency selectively effective in said circuit.

12. In an electrical musical instrument, the combination which comprises a series of sources of octavely related square wave oscillations, a plurality of first output terminals, a resistive path connected between each first terminal and a corresponding source supplying square wave signal of predetermined frequency to said first terminal, a plurality of second output terminals, a set of resistive paths for and connected between each second terminal and a corresponding group of octavely adjoining sources and having such relative impedances as to additively combine the square wave signals drawn from said group of sources into a saw tooth wave at the said second terminal, a square wave output bus bar and a saw tooth wave output bus bar, a switching key interposed between each first terminal and said square wave bus bar and between each second terminal and said saw tooth wave bus bar adapted when actuated to render square and saw tooth wave signals of different frequencies effective in the respective bus bars, a main output bus bar, and filter networks connected between both the square and the saw tooth wave bus bars and the main output bus bar to transfer signals of modified harmonic composition to said main bus bar.

13. In an electrical musical instrument, the combination which comprises a plurality of sources of octavely related square wave oscillations, an output terminal for each of said sources constituting a first set, coupling elements for connecting each of said sources to the corresponding terminal, a second set of output terminals, coupling elements supplying square wave signal at predetermined relative amplitudes from selected groups of octavely adjoining sources to each of said second set of terminals and combining such signals into octavely related sawtooth wave signals at the several terminals, a preliminary output bus bar for each of said sets of terminals, a switch connected between each terminal of both sets and their respective preliminary output bus bars, a key for each pair of switches coordinated to square and sawtooth

wave signals of equal fundamental frequency adapted when actuated to render square and sawtooth wave signals of corresponding frequency simultaneously effective in their respective preliminary output bus bars, a main output bus bar and a switch and coupling elements connected between each of said preliminary output bus bars and the said main output bus bar to make signals of square and sawtooth waveform selectively effective in said main output bus bar.

- 5 14. In an electrical musical instrument, the combination which comprises a plurality of sources of octavely related square wave oscillations, a square wave and a sawtooth wave terminal for each of said sources constituting a pair, a resistive path connecting each of the square wave terminals of said pairs to its corresponding source, a set of resistive paths connecting each of the sawtooth wave terminals of said pairs to a selected group of octavely adjoining sources, a square and a sawtooth wave preliminary output bus bar, a switch connected between each of said terminals and their respective preliminary output bus bars, a key for each pair of switches adapted when actuated to render square and sawtooth wave signals of corresponding frequency simultaneously effective in their respective preliminary output bus bars, a main output bus bar, a plurality of filter circuits, and switching means for selectively connecting said filter circuits between said preliminary and main output bus bars to make signals of modified harmonic composition effective in the main output bus bar.
- 20 15. In a system for synthetizing sawtooth wave currents from square wave currents, the combination which comprises a plurality of sources of square wave currents the frequencies of which are respectively proportional to successive powers of 2, an output circuit in common for said sources, and a coupling element for each of said sources interposed between the corresponding source and the said output circuit, the first one of said coupling elements having such impedance as to supply square wave current of predetermined amplitude from the lowest frequency source to said output circuit, and the other coupling elements having such impedances as to supply square wave currents of progressively decreasing amplitudes from the higher frequency sources to said output circuit, the relative impedances of said coupling elements being so determined with respect to the original amplitudes of the square wave currents generated by said sources as to additively combine said square wave currents in said output circuit into an approximate sawtooth wave current.
